(57) **CLAIM**

The ornamental design for a handheld 3D scanner as shown and described.

DESCRIPTION

1. Handheld 3D scanner

1.1 : Front

1.2 : Back

1.3 : Left

1.4 : Right

1.5 : Top

1.6 : Bottom

Handheld 3D scanner is mainly used to photograph and scan spaces or objects, and generate VR; for example: to photograph and scan housing, and generate VR models.

(Continued)

The broken lines in the drawings are for the purpose of illustrating portions of the handheld 3D scanner that form no part of the claimed design.

1 Claim, 6 Drawing Sheets
